UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

LOCK.

Application filed June 2, 1922. Serial No. 565,332.

To all whom it may concern:

Be it known that I, JOHN B. FREYSINGER, a citizen of the United States, and a resident of Stamford, in the county of Fairfield and State of Connecticut, have invented certain new and useful Improvements in Locks; and I do hereby declare the following to be a full, clear, and exact description of the invention, such as will enable others skilled in the art to which it appertains to make and use the same.

This invention relates to improvements in locks for doors and the like,—one object of the invention being to provide in a lock construction, a main bolt structure and an auxiliary dead-locking bolt structures which shall be carried by the main bolt structure and have members vertically movable in opposite direction relatively to each other to interlock with the keeper when the main bolt structure is projected thereinto, whereby jimmying of the lock structure to separate the keeper and lock casing or otherwise picking the lock to withdraw the bolt from the keeper will be prevented.

A further object is to provide a lock construction of the "rim-lock" type having the characteristics above outlined, in which no part of the lock casing shall project beyond the vertical edge of the door and may be flush therewith, and in which no part of the keeper will overlap the lock casing.

With these and other objects in view, the invention consists in certain novel features of construction and combinations of parts as hereinafter set forth and pointed out in the claims.

In the accompanying drawings; Figure 1 is a longitudinal sectional view of a lock structure embodying my improvements; Figure 2 is a rear face view with the cover plate of the lock casing removed; Figure 3 is an edge view of the main bolt structure; Figure 4 is a face view of the main bolt structure; Figure 5 is an edge view of one of the auxiliary bolt structures; Figure 6 is a face view of the same; Figure 7 is a side view of the other auxiliary bolt structure; Figure 8 is a face view of the structure shown in Figure 7; Figure 9 is a sectional view partly in elevation showing the bolt in retracted positions, with certain parts

of the operating mechanism omitted; Figure 10 is a transverse sectional view of the structure shown in Figure 9 with the bolts projected, but omitting the keeper, and Figure 11 is a view similar to Figure 9, but omitting the keeper and showing the bolts projected.

In the drawings, I have represented my improvements with a lock of the "rim" type, but it will be understood that said improvements might be embodied in locks of other types. The casing 1 of the lock may be secured in any suitable manner to a door so that one end thereof will be flush with the vertical free edge of said door and the keeper 2 may be secured to the door frame or jamb so as to be flush or in alignment with the inner face of said jamb. The keeper 2 is provided at its open side with lugs or cross members 3, 3, which are so spaced apart and from the upper and lower walls of the keeper as to provide openings 4, 5, 6 for the passage into the keeper of the bolt members carried by the lock casing as more fully hereinafter described.

The main bolt structure 7 of the lock comprises a plurality of bolt members 8, 9 and 10 carried by and integral with a body or apron member 11 mounted to slide in the casing 1. The body portion of the main bolt carries a talon 12 to be engaged by one or another cam pin 13 carried by a cross head 14 secured to the spindle 15 of a knob 16 for projecting or retracting the bolt. The knob spindle and cross head may be held in the position to which they may be turned, by means of the arms 17 of a friction spring 18, as shown in Figure 2.

The members 8 and 9 of the main bolt structure are made hollow as indicated in Figures 1 to 4 and 9 and 11 and the intermediate member 10 is provided in its upper and lower sides with sockets or recesses 19 and 20. The free ends of the several members 8, 9, 10 of the main bolt structure lie flush with the front end of the casing when said main bolt structure is in withdrawn or retracted position and said end of the casing is provided with a plurality of openings for the passage of said bolt members.

Auxiliary or dead-locking bolt structures 21 and 22, shown separately in Figures 5-6

and 7-8 are carried by the main bolt structures so as to be movable transversely of the same,—the body portion of said main bolt structure being made with guideways 23, 24 and a transverse rib 25 for the accommodation of and cooperation with the bolt structures 21 and 22 to insure free transverse movement of the latter. The auxiliary bolt structure 21 comprises a body portion 26 having a rib 26^a to move in the guideway 24 and provided at one end with an arm 27 which straddles the rib 25 on the main bolt structures and enters the hollow bolt member 8 of the latter,—said arm 27 carrying a vertical bolt member 28 to be projected across the space between the main bolt members 8 and 9 and enter the recess 19 in the intermediate bolt member 10 when the bolts are projected into the keeper as shown in Figure 2. The auxiliary bolt structure 22 comprises a body portion 29 movable in the guideway 23 of the main bolt and having at its lower end, a forwardly projecting arm 30 which enters the lower hollow main bolt member 9 and provided with an auxiliary bolt member 31 adapted to project across the space between the main bolt members 9 and 10 and enter the recess 20 in the under side of the intermediate main bolt member when the bolts are projected into the keeper. Thus it will be seen that when the main bolt is projected into the keeper, the auxiliary bolts will be caused to have interlocking connection with the projected members of the main bolt and also with the keeper behind the lugs or cross members 3 thereof, and forcing of the lock casing and keeper with the use of a jimmy or other burglar's tool will be rendered impossible.

With my improvements, the auxiliary bolt structures are caused to move respectively in opposite directions when projected or retracted and they will be locked in such respective positions, and when the main bolt is in retracted position within the lock casing, the auxiliary bolt members 28 and 31 will be housed within the hollow main bolt members 8 and 9 as indicated in Figure 9. In accomplishing these results, the instrumentalities now to be explained are employed:

A lever 32 is pivotally connected, as at 33, with the main bolt and is provided at its respective ends with slots 34, 35 to engage pins 36, 37 on the body portions of the auxiliary bolt structures 21 and 22 respectively, as indicated in Figure 2. The body portion of the auxiliary bolt structure 21 is provided on its bottom side with projections 38—39 to be engaged by one of the cam pins 13 of the cross head 14 for moving the auxiliary bolt structures, as presently more fully explained. A lever 40 is pivotally connected at one end, on a pin 41, to the upper portion of the auxiliary bolt structure 21 and

is provided between its ends with a rearwardly projecting arm 42 which enters between the lugs 38 and 39 in position to be engaged by one of the cam pins 13. The lever 40 is also made with a depending L-shaped arm 43, the lower portion of which projects rearwardly and terminates in position to so engage a lug 44 on the main bolt structure as to normally lock the auxiliary bolt structures against movement when the latter are in either projected or retracted positions, and said lever is maintained in and returned to its normal position as shown in Figure 2, by the action of a spring 45 attached at one end to a pin 46 on the lever arm 43 and at the other end to a pin 47 on the main bolt structure.

Assuming that the bolts are projected as indicated in Figure 2, and it is desired to retract the same to unlock the door, the operator may turn the knob and effect movement of the cross head 14 to cause the lever cam pin 13 to travel upwardly in the arc of a circle. During the initial portion of such upward travel of the cam pin, it will engage the arm 42 of the locking lever 40 and so turn the latter on its pivotal support as to move its L-shaped arm 43 from beneath the lug 44 on the main bolt structure and thus release the auxiliary bolt structures from locked connection with said main bolt structure. As the cam pin 13 continues to move upwardly, it will engage the lug 38 and thus move the auxiliary bolt structure 21 upwardly and, by reason of the lever connection 32, cause the auxiliary bolt structure 22 to move downwardly,—thus withdrawing the two auxiliary bolt members 28 and 31 into the hollow main bolt members 8 and 9 respectively. As the cam pin 13 continues to move upwardly in the arc of a circle, it will enter the talon 12 of the main bolt structure and and retract the latter together with the auxiliary bolt structures, into the lock casing. It will be seen that when the bolts are projected as shown in Figure 2, the auxiliary bolt structures will be locked against movement by the lever arm 43 projecting under the lug 44, and it will be understood that when said auxiliary bolt structures are in retracted positions, they will be locked against movement by the lever arm 43 projected over said lug 44.

I have hereinbefore described knob operated means for controlling the operation of the lock but it will be understood that key operated means may be provided also to operate the lock from the outside of the door. In Figure 1 of the drawing, I have indicated a roll back cam 48 carried by the cover plate 49 of the casing.

Various changes might be made in the details of construction of my invention without departing from the spirit thereof or

limiting its scope and hence I do not wish to restrict myself to the precise details herein set forth.

Having fully described my invention 5 what I claim as new and desire to secure by Letters-Patent, is:—

1. In a lock structure, the combination with a lock casing and a keeper, of a main bolt structure including spaced bolt members to enter the keeper, two vertically movable auxiliary bolt structures carried by the main bolt structure and including bolt members to be projected across spaces between said main bolt members, a lever pivoted between its ends to the main bolt structure and having connections with the respective auxiliary bolt structures, and manually operable means including a cam pin to engage one of said auxiliary bolt structures and 20 cause the two auxiliary bolt structures to be moved simultaneously in opposite directions.

2. In a lock structure, the combination with a lock casing and a keeper, of a main bolt structure including spaced bolt members to enter the keeper, two vertically movable auxiliary bolt structures carried by the main bolt structure and including bolt members to be projected across spaces between 30 said main bolt members, a lever pivoted between its ends to the main bolt structure and having connections with the respective auxiliary bolt structures, manually operable means including a cam pin to engage one 35 of said auxiliary bolt structures and cause the two auxiliary bolt structures to be moved simultaneously in opposite directions, and locking means for said auxiliary bolt structures and having a part positioned

to be operated by said manually operable means to operate said locking means to release the auxiliary bolt structures.

3. In a lock structure, the combination with a lock casing and a keeper, of a main bolt structure including spaced main bolt members to enter the keeper, two vertically movable auxiliary bolt structures carried by the main bolt structure and including bolt members to be projected across the spaces between the main bolt members, means connecting the auxiliary bolt structures whereby the same may be caused to move simultaneously in opposite directions, manually operable means including a cam pin for operating said auxiliary bolt members, a lug on the main bolt structure, a lever pivoted to one of said auxiliary bolt members and having a depending arm to cooperate with said lug to lock the auxiliary bolt structures in either projected or retracted positions, a spring normally tending to move and hold the lever in cooperation with said lug, said lever having an arm in position to be engaged by the manually operable cam pin to release the auxiliary bolt structures from locked relation to the main bolt structure, and means on the main bolt structure to be engaged by the manually operable cam pin to project or retract the main bolt and the auxiliary bolt structures carried thereby 70 relatively to the keeper.

In testimony whereof, I have signed this specification in the presence of two subscribing witnesses.

JOHN B. FREYSINGER.
